(57) **CLAIM**

The ornamental design for an electrical connector, as shown
and described.

DESCRIPTION

FIG. 1 is a front perspective view of our new design for an
electrical connector;
FIG. 2 is another front perspective view thereof;
FIG. 3 is a front elevation view thereof;
FIG. 4 is a back elevation view thereof;
FIG. 5 is a right-side elevation view thereof;
FIG. 6 is a left-side elevation view thereof;
FIG. 7 is top plan view thereof;
FIG. 8 is a bottom plan view thereof; and
FIG. 9 is a back perspective view thereof.

The broken lines in the drawings are included for the purpose
of illustrating environmental subject matter and form no part
of the claimed design.
